Attorney

UNITED STATES PATENT OFFICE.

HENRICUS MARTINUS RAGETLIE, OF BAARDWIJK, NETHERLANDS.

UNITARY WRITING-DESK AND SEAT.

1,208,003.

Specification of Letters Patent. Patented Dec. 12, 1916.

Application filed August 29, 1916. Serial No. 117,391.

To all whom it may concern:

Be it known that I, HENRICUS MARTINUS RAGETLIE, subject of the Queen of the Netherlands, and resident of Baardwijk, the 5 Netherlands, have invented certain new and useful Improvements in Unitary Writing-Desks and Seats, of which the following is a specification.

This invention relates to unitary writing 10 desks and seats, in which the desks and seats are adjustable; such devices being particularly intended for use in schools and the like.

Heretofore the use of such unitary desks 15 and seats has not been extensive owing to the complicated character thereof and to the fact that they have not satisfied requirements as to adjustability and general utility.

According to this invention the improved 20 writing desk is readily adjustable to suit normally developed children or adults, the arrangement being such that the necessary adjustments are effected simultaneously so as to retain the desk and seat in correct relative position for obtaining ease and comfort 25 in writing. The arrangement, however, is such that the seat and desk may be independently adjusted to suit persons having abnormal bodies.

30 In order that the said invention may be clearly understood and readily carried into effect, the same will now be described with reference to the preferred embodiment illustrated in the accompanying drawing, in 35 which an elevation of the device showing the parts in the extreme positions of adjustment in full and broken lines respectively.

In the figure *a* represents the fixed part (frame) of the device, *b* the vertically adjustable desk frame and *c* the desk leaf connected to slide forward and backward on the latter. The seat *e* is similarly connected to the seat frame *d* which is vertically and horizontally adjustable; the seat back is 45 indicated by *f*.

The desk frame *b* and the seat frame *d* may be adjusted simultaneously or independently to the desired height, through the intervention of screw spindles *i* and *k*, the 50 latter spindle being suitably inclined as shown in the drawing. Motion is imparted to the two screw spindles by an intermediate spindle *g'* which is provided at its respective ends with bevel wheels *h* and *g*.

55 The bevel wheel *h* engages with a similar wheel *h'* carried by the lower end of the

spindle *i* and the bevel wheel *g* with a bevel wheel *g'* carried by a shaft *g* adapted to be rotated by a crank or similar device applied to the end thereof. Bevel wheel *g'* is also in 60 mesh with a similar wheel *g* carried by the lower end of the spindle *k* so that when the shaft *g* is rotated both the screw spindles *i* and *k* will be operated. The desk and seat frames *b* and *d* may be provided with 65 threaded orifices or nuts for engaging with the spindles *i* and *k* so that said frames will traverse the spindles when they are rotated. The adjustable desk frame *b* bears a journal 70 *l* acting as the fulcrum of a rotatable bell crank lever; the latter is connected at one end with the fixed frame by means of the link *n*, at the other end with the movable desk leaf *c* by means of the member *o*. In the same way a bell crank lever *q* rotatable 75 about the journal *p* of the adjustable seat frame *d*, is connected at one end with the fixed frame *a* by means of the link *r*, at the other end with the movable seat *e* by means of the link *s* and the seat back *f*—which is 80 vertically slideable on the seat frame *d*—by means of the link *t*.

It is obvious that a rotation of the bevel wheel *g* causes the desk frame *b* to rise by means of the screw spindle *i*, the seat frame 85 *d* to rise and to move at the same time backward by means of the screw spindle *k* while the desk leaf *c* will move at the same time backward, the seat *e* forward and the seat back upward. 90

The position of the different parts for maximum adjustment is indicated by broken lines, and the corresponding reference letters are marked with accents.

The rate of the adjustment of the movable 95 parts depends upon the transmission rate of the bevel wheel gears, the pitches of the screw spindles *i* and *k* and the length and arrangement of the members connecting the fixed with the movable parts of the desk and 100 seat. The respective rates of adjustment are designed to accord with requirements. In order to render it easier for the child or adult to sit down or leave the desk the lower part *u* of the desk leaf *c* may be made reversible. This part *u* is marked in its reversed position by *u''*.

By providing a coupling or similar device which is easily engaged or disengaged, the desk and the seat may be independently adjusted. 110

Having now described my invention, what

I claim as new and desire to secure by Letters Patent is:—

1. In a unitary writing desk and seat, the combination of a main frame, two frames adjustably mounted thereon, a seat slidably supported on one of said adjustable frames, a desk leaf slidably supported on the other adjustable frame, means for effecting the vertical movement and separation of said adjustable frames, and means for slidably displacing the desk and seat with respect to their supporting frames.
2. In a unitary writing desk and seat, the combination of a main frame, a frame adjustably mounted on one end of said main frame, a frame adjustably mounted on the main frame some distance from the other adjustable frame, a folding desk leaf slidably supported on one of the adjustable frames, a seat slidably supported on the other adjustable frame, means for effecting the vertical adjustment and distance of separation of said adjustable frames, and means operated simultaneously with the aforesaid means for slidably displacing the desk and seat with respect to their supporting frames.
3. In a unitary writing desk and seat, the combination of a main frame, a frame adjustably mounted on one end of said main frame, a frame adjustably mounted on the main frame a suitable distance from the other adjustable frame, a desk leaf slidably supported on one of the adjustable frames, a seat slidably supported on the other ad-

justable frame, operating gear for effecting the vertical adjustment and distance of separation of said adjustable frames, and link mechanism effective when the adjustable frames are moved to displace the desk and seat with respect to their supporting frames.

4. In a unitary writing desk and seat, the combination of a fixed main frame, an adjustable seat frame, a seat slidably mounted on said seat frame, a back for said seat, link mechanism for connecting the seat and back with the seat frame and main frame, a desk leaf slidably mounted on said desk frame, link mechanism for connecting the desk leaf with the desk frame and main frame, said link mechanisms imparting movement to the seat and seat back and desk leaf when the seat and desk frames are adjusted.

5. In a unitary writing desk and seat as herein set forth, the combination of an adjustable seat frame, a seat slidably mounted on said seat frame, a back adjustable with respect to said seat, an adjustable desk frame, a desk leaf slidably mounted on said desk frame, and means for effecting the simultaneous adjustment of all of said elements to suit the body dimensions of children or adults.

Signed at Scheveningen the Netherlands this 3d day of July A. D. 1916.

HENRICUS MARTINUS RAGETLIE.
